J. York, Jr.

Re-Sawing Mach.

№ 104,681. Patented Jun. 21, 1870.

Fig. 1.

United States Patent Office.

JAMES YORK, JR., OF MONROE, MICHIGAN.

Letters Patent No. 104,681, dated June 21, 1870.

IMPROVEMENT IN RE-SAWING MACHINES.

The Schedule referred to in these Letters Patent and making part of the same.

To whom it may concern:

Be it known that I, JAMES YORK, of Monroe, in the county of Monroe and State of Michigan, have invented a new and useful Improvement in Re-sawing Attachments to Planing-Machines; and I do declare that the following is a true and accurate description thereof, reference being had to the accompanying drawing and to the letters of reference marked thereon and being a part of this specification, in which—

Figure 1 is a perspective view of my device, attached to a planing-machine.

Figure 2 is a rear elevation of the same, detached. Like letters refer to like parts in each figure.

The nature of this invention relates to an improved re-sawing device, attached to and operated by the mechanism of a planing-machine, so that a board may be planed on both sides, and split by a horizontal circular-saw in once passing through the planer. It consists in the combination and arrangement of its several parts, consisting of a detachable frame-work, bolted to the front or discharge end of a planer, in which frame-work a circular oscillating frame is pivoted, and in which is stepped a vertical mandrel, carrying a horizontal circular-saw, the mandrel being driven by a quarter-turn belt from the drum of the planer. The circular frame is so arranged that the saw may be raised or lowered, to split boards of any thickness, and the saw inclined so as to split them at a bevel, as may be desired.

In the drawing—

A represents the frame of a planing-machine; and B the drum, which carries the belts, driving its various cutter-heads and feed-gear.

C is a metallic frame, supporting the saw-table D, which is secured to the end of the planer-bed by proper screws, passing through slots, a, in the corners of the saw-table, so as to attach it to planers of various widths. The lower ends of the frame are secured to the legs of the planer by bolts passing through the bar b into the legs, as shown.

E is a brace, extending across and secured to the vertical standards of the frame C, in a slot, c. In the

brace is pivoted an oscillating circular frame F, its pivot projecting through the slot c, to permit the frame to be raised and lowered by a set-screw, g, at the back of the brace, operating on the threaded collar of the pivot for that purpose. The circular frame is secured in position by screws, d, on proper studs in the brace E, projecting through the slots e of the circular frame.

G is a vertical mandrel, stepped and journaled in the front of the circular frame, driven by a quarter-turn belt, passing from the drum B around its pulley f.

H is a horizontal circular-saw, secured to the mandrel by proper nuts.

I is a gauge, adjustable to or from the saw, against which the outer edge of the board travels and is guided. The outer end of this gauge is turned to a right angle to form a splitter, i, which enters the kerf of the board being sawed, and prevents its upper half from binding the saw.

J is a gauge for guiding the inner edge of the board, and is adjustable in its slot in the saw-table by a screw, j, as shown.

It will be readily seen that this device may be easily attached to planers of various makes and sizes, saving the first cost of a re-sawing machine, and the expense of operating it; that boards may be re-sawed by it at an angle, for weather-boarding, or a thick and a thin board may be sawed from one plank, and the device may be quickly removed from the planer when not needed.

What I claim as my invention, and desire to secure by Letters Patent, is—

The combination and arrangement of the adjustable circular frame F, the slot c, the brace E, the screw g, the mandrel G, the saw H, the frame C, and the table D, when constructed and operating as and for the purposes aforesaid.

JAMES YORK, JR.
